UNITED STATES PATENT OFFICE.

VERNON HOXIE, OF ADRIAN, MICHIGAN.

STAPLE FORMING AND DISCHARGING MECHANISM.

No. 879,965.

Specification of Letters Patent.

Patented Feb. 25, 1908.

Application filed July 5, 1907. Serial No. 382,247.

To all whom it may concern:

Be it known that I, VERNON HOXIE, a citizen of the United States, and a resident of Adrian, in the county of Lenawee and State 5 of Michigan, have invented a certain new and useful Staple Forming and Discharging Mechanism; and I do hereby declare the following to be a full, clear, and exact description of the invention, such as will enable others skilled in the art to which it appertains to 10 make and use the same, reference being had to the accompanying drawings, and to the figures and letters of reference marked thereon, which form a part of this specification.

15 My invention relates to wire-working machines, and particularly to wire-staple forming mechanism for use in wire-fabric machines, which mechanism is designed to form a staple from a section of wire fed thereto, discharge it therefrom and finally clamp it about the intersecting portions of a fabric, the wires of which are intermittently fed by suitable mechanism in a plane intersecting the plane of discharge of said staples.

20 The object of my invention is to simplify and improve upon the construction and operation of apparatus of this class, whereby to enhance the practicability and commercial value thereof.

25 The operation, construction and arrangement of the parts of the invention are fully described in the following specification and illustrated in the accompanying drawings, in which,—

30 Figure 1 is a side elevation of a portion of a loom equipped with my invention and illustrating an associated operating mechanism. Fig. 2 is a side elevation of the mechanism comprising my invention with one side of the 35 inclosing casing removed. Fig. 3 is a section of the same on the line *a a* in Fig. 2. Fig. 4 is a transverse section on the line *b b* in Fig. 5. Fig. 5 is a view similar to Fig. 2 with the plunger nearing the completion of its forward 40 movement. Fig. 6 is an enlarged section on the line *b b* in Fig. 5 with a staple lying in advance of the discharging plunger. Fig. 7 is a perspective view of the pressure-block, which 45 cooperates with the staple during the forming operation. Figs. 8 and 9 are interior views of a slightly modified form of the invention with the plunger shown in different positions, and Figs. 10 and 11 are transverse sections on the line *c c* in Fig. 8 at different 50 points of movement of the plunger.

55 Referring to the drawings, 1 and 2 designate the longitudinally separable parts of the holder or member within which the forming and discharging means of my invention are mounted. The parts 1 and 2 have their inner faces provided with longitudinal recesses or slide-ways 3 and 4, respectively, in which the plunger 5 is reciprocally mounted, the latter of said recesses being of greater length than the other and broadened to permit the 60 movement therein of the staple-forming plate 6, which is attached to the forward end of the plunger. This plate is provided at its forward end with a recess 7, which, on the forward movement of the plunger, is intended 65 to coöperate with a fixed alining tongue or rib 8 to form a severed section of the wire 9 into a U-shaped staple 9', as shown. Mounted in an opening 10 in the part 2 and straddling the tongue or rib 8 is a U-shaped pressure-block 11, which is yieldingly held by a spring 12 with its leg terminals normally disposed in the path of movement of the plate 6. The legs of the block closely hug the sides of 70 the tongue 8, and are intended to operate to 75 eject a staple laterally from the tongue after the staple has been formed and the plate 6 has receded from over the block. The plate 6 on its forward movement has contact with the inclined surfaces 11' of the block and 80 causes the block to move outwardly against the tension of the spring 12 out of the path of 85 movement of the plate.

85 The staple after being formed is discharged from the apparatus and driven around the intersecting wires of a fabric by the discharging tongue 13. This tongue rigidly projects from the forward end of the plunger 5 and lies in a plane which preferably intersects at right angles that of the plate 6, as shown, 90 thus causing the staples to describe a quarter turn as they are ejected from the rib or tongue 8 by the block 11 and to fall flat upon the upper face of the tongue 13 in position to drop in advance thereof as it recedes from 95 under the same. The tongue 13 operates in the bottom of a chamber 14 and through an alining discharge passage in the forward end of the part 1, as shown, the chamber 14 being of suitable size to permit the staples to fall 100 freely from their forming to their discharging position, as shown.

105 16 designates a guide-finger which is shown as being carried by the part 1 in contact with the face of the rib or tongue 8 and as curving 110

outwardly and downwardly therefrom, as shown in Figs. 3, 4 and 6. The purpose of this finger is to guide the movement of the staples as they drop from one position to the other so that instead of permitting the same to fall straight and rest upon one leg on the discharging tongue 13 they are caused to describe a quarter turn and fall flat upon said tongue, as best shown in Fig. 6.

10 The wire 9 is intermittently fed to the forming parts through an apertured die 17 mounted in the parts 1 and 2 and through alining grooves 18 provided in the inner faces of the rib or tongue 8 and the legs of the block 11 adjacent their rear ends, as shown. 15 On the forward movement of the forming-plate 6 the staple-section is severed from its thread by the shearing action of the point 6' of the plate against the face of the die 17.

20 In Fig. 1 is illustrated a simple mechanism for intermittently feeding a length of wire to the staple-former and operating the plunger 5. In this figure 21 may designate a drive-shaft, which carries a gear 22 for meshing with the two opposing gears 23 and 24. On the shaft with the former is mounted a semi-gear 25 which meshes with a semi-pinion 26 on the shaft 27 and through it communicates rotation to the gear 28, which drives the small gear 29 through the medium of the idler-gear 30. The gear 29 is carried by one of a pair of feed-rolls 31 between which the wire 9 passes and is frictionally gripped to cause it to be fed to the forming apparatus when said rolls 35 are rotated, thus causing a properly timed intermittent movement to be communicated to said wire from a continuous rotation of the gear 22. Mounted on the shaft with the gear 23 is an eccentric 32 carrying an eccentric-rod 33, which connects with knuckles 34 and through them imparts a reciprocatory movement to the plunger 5 of the associated staple-forming apparatus.

40 The modification shown in Figs. 8, 9, 10 and 11 consists in the provision of means for use in lieu of the guide-finger 16 for causing a positive turning of the staples from their forming to their discharging positions. The change consists in extending the chamber 14 through to the top of the part 1, as shown at 45 *a*, and mounting a block *b* therein, which block is yielding held in lowered position by a spring *c*. The inner end of this block is transversely rounded, as shown at *d*, to adapt it when pressing inwardly against one leg of a staple standing up in the position shown in Fig. 10 to cause positive movement of the staple to reclining position, as shown in Fig. 11. During the forming of a staple the block 55 *b* is raised above the same by the coaction therewith of the finger *e*, which is fixed to the side of the plunger 5 and travels in a runway *f* in the part 1, as shown. This finger has its nose beveled, as at *g*, to adapt it to enter a transverse recess *h* in the side of the block *b*.

60 and force the block to elevated position during the forming of a staple. It is thus apparent that as the block 11 forces the staple from the rib 8 on the recession of the plate 6 therefrom, the straightening-block *b* will be released from the finger *e* and caused by the spring *c* to move inwardly and effect a straightening of the staple in position to be engaged by the discharging-tongue 13 on its forward movement.

65 The operation of the invention is as follows:—During each rearward movement of the plunger 5 and after the plate 6 has receded past the die 17 a section of wire 9 is fed to the forming parts by a properly timed movement of the feeding mechanism. On the forward movement of the plunger the plate 6 both severs the wire and forms the severed section into U-shape around the rib or tongue 8, the pressure-block 11 being forced outwardly by the contact of the plate therewith. 70 The plunger and plate then recede to permit the pressure-block 11 to force the staple from the rib 8 and cause it to fall to the bottom of the chamber 14 upon the discharging-tongue 13, which is receding with the plunger, the falling movement of the staple being guided either by the guide-finger 16 or the action of the block *b* so that the staple will lay flat upon the discharging-tongue. The 75 plunger recedes sufficiently for the staple to drop in advance of the tongue 13, and on the subsequent forward movement of the plunger the staple is discharged from the apparatus and clamped around two of the wires 80 at their points of intersection or other alining object. It is thus apparent that while one 85 staple is being formed another is being discharged.

90 I wish it understood that I do not desire to 95 be limited to the exact details of construction shown and described, as obvious modifications will occur to a person skilled in the art; and also that while I have particularly described my invention as being for use in connection with a wire fabric machine the same 100 may be used separately or in connection with other machines for similar or analogous purposes, without departing from the spirit of the claims.

105 Having thus described my invention, what I claim as new and desire to secure by Letters Patent, is,—

110 1. In a machine of the class described, an incasing member, a fixed rib therein about 115 which a staple is formed, a reciprocatory member coöperating with the rib to form a staple from a section of wire fed to the incasing member, a discharging element movable with the reciprocatory member and disposed in a plane intersecting the surface plane of the plunger, said incasing member having a chamber contiguous to said rib 120 within which a formed staple is permitted to have a free circular falling movement to 125 130

move from forming to discharging position, and means for ejecting the staple from the rib after being formed.

2. In a staple machine, an incasing member having a fixed staple-forming part, a non-rotatable plunger having a staple-forming part and a staple-discharging part disposed in intersecting planes, the staple-forming part coöperating with the fixed staple-forming part to form a staple, and a pressure-block operative to eject the formed staple from said fixed part to permit it to move into position to be engaged by the discharging part.

3. In a staple machine, an incasing member, a plunger having a staple-forming part and a staple-discharging part disposed in intersecting planes, a fixed portion within the member with which the forming part co-
20 operates to form a staple, and a pressure-block U-shape in cross-section which straddles said fixed portion and effects an ejection of the formed staple therefrom at a predetermined point in the movement of the
25 plunger to permit the staple to move into position to be discharged.

4. In a staple machine, an incasing member having a fixed forming rib and a chamber at the side of the rib, a staple-forming part and a staple-discharging part operative in said member and disposed in intersecting planes in different portions of said chamber, the forming part coöperating with the rib to form a staple from a section of wire fed to the member, and a member movable to eject a formed staple from said rib to permit it to freely fall in said chamber in position to be discharged by the discharging part.

5. In a staple machine, an incasing member having a fixed staple-forming rib, a staple-forming element and a staple-discharging element movable in unison in said member and having their flat sides disposed in intersecting planes, the forming element coöperating with said rib to form a staple, and means for ejecting a staple from the rib after being formed to permit it to fall by gravity and turn from forming to discharging positions.

6. In a staple machine, an incasing member, a portion in said member about which a staple is formed from a section of wire fed thereto, mechanism operative in said member to simultaneously act on a section of wire to shape it about said portion and to discharge a previously formed staple from said member, the forming and discharging parts of said mechanism being relatively positioned to cause a staple to have a lateral turning movement in moving from one to the other and an element straddling the forming portion in said member and automatically operative to eject a staple therefrom to permit it to drop by gravity to discharging position.

7. In a staple machine, an incasing member, a portion in said member about which a

staple is formed, forming and discharging parts operative in said member to simultaneously act on a section of wire fed thereto to shape it about said portion and to discharge a previously formed staple from said member, said parts being relatively positioned to cause a staple to have a lateral circular movement in moving from its forming to its discharging position, and means for ejecting a formed staple from said portion when the forming and discharging parts have receded from their forming and discharging positions.

8. In a staple machine, an incasing member, a portion in said member about which a staple is formed, mechanism coöperating with said portion to form a staple from a section of wire fed thereto and operating to discharge a formed staple from the member, the forming and discharging parts of said mechanism being relatively disposed to cause a staple to have a lateral turning movement as it moves from its forming to its discharging position, and means for causing a staple to turn as it falls by gravity from one position to the other.

9. In a staple machine, an incasing member, a portion in said member about which a staple is formed, a tool operative in said member to form and discharge a staple, the forming and discharging parts thereof being relatively positioned to cause a staple to have a lateral turning movement in moving from one to the other, means for ejecting a formed staple from said portion, and means for causing a staple to have a turning movement as it moves by gravity from one to the other of said parts.

10. In a staple machine, an incasing member having a chamber therein, a fixed staple forming portion facing said chamber, a tool operative in said member to form and discharge a staple, the forming and discharging parts thereof being relatively positioned to cause a staple to have a lateral turning movement within the chamber in moving from one to the other of the parts, means for ejecting a staple from said forming portion into the chamber, and means within the chamber for causing a staple to have a turning movement as it moves by gravity from one to the other of said parts.

11. In a staple machine, a member having two ways disposed transversely in intersecting planes therein and a fixed forming part provided in one way, said member also having a chamber which faces the forming part and opens communication between the two ways, means operating in said two ways to simultaneously form a staple about said part and eject a previously formed staple from the other way, means straddling the part for ejecting a formed staple therefrom into said chamber on a recession of said mechanism, and means for causing a staple as it falls into

said chamber to describe a partial revolution to move from the plane of one way to that of the other.

12. In a staple machine, an incasing member, a fixed staple-forming part in said member, mechanism coöperating with said fixed part to form a staple and operating to discharge a formed staple from the member, the forming and discharging parts of said mechanism being relatively positioned to cause a staple to have a lateral turning

movement to move from forming to discharging positions, and non-rotatable means for causing a staple to turn from one position to the other after being formed.

In testimony whereof I have hereunto signed my name to this specification in the presence of two subscribing witnesses.
